AMUSEMENT RIDE

Norman Bartlett, North Tonawanda, N. Y., assignor of one-half to Marjorie Bartlett, North Tonawanda, N. Y.

Application March 16, 1944, Serial No. 526,706

17 Claims. (Cl. 272—40)

1

This invention relates to amusement apparatus and particularly to amusement rides of the general type involving aerial passenger cars.

Various amusement rides have previously been proposed wherein a central rotatable support structure has suspended therefrom, or otherwise supported thereby, a circular series of passenger carrying cars, the cars being adapted to move upwardly and outwardly under the centrifugal forces generated by rotation of the central support structure.

In one of its aspects of novelty the present invention provides an aerial car amusement ride which has secondary means for intercepting the cars as they approach a position of rest and for supporting the cars in a predetermined rest position, which arrangement permits the use of a ride of given capacity in a much smaller space than has hitherto been possible.

In the amusement ride hereinafter described in detail the several cars are suspended from a central support structure in such a way that they move upwardly and outwardly under centrifugal force. An important aspect of novelty of the present invention resides in the fact that the path which the several cars would normally follow, if subject to centrifugal force alone, is modified by the application of other forces, so that the several cars or passenger carriers travel in an undulating circular path. According to the present invention the additional component of movement which is thus introduced may be positive and definite, or it may be applied through yieldable means so that the centrifugal and inertia forces acting on the cars are yieldably opposed by a modifying influence.

The foregoing and other objects and advantages of the present invention will become apparent from the following detailed description of typical embodiments thereof taken in conjunction with the accompanying drawings. While a full disclosure of exemplary embodiments of the present invention is included in this application, it is to be understood that the principles of the invention are not limited thereto or otherwise than as defined in the appended claims.

In the drawings:

Fig. 1 is a general elevational view of one form of the amusement ride of the present invention;

Fig. 2 is an enlarged fragmentary elevational view showing one of the car supporting arms and the flexible car suspension means associated therewith;

Fig. 3 is a vertical central cross sectional view, on a still further enlarged scale, showing one form of the central car supporting structure;

2

Fig. 4 is a detailed cross sectional view through the auxiliary car supporting and spacing means, and,

Fig. 5 is a fragmentary cross sectional view of a modified form of car supporting arm viewed as in Fig. 3.

Throughout the several figures of the drawings like characters of reference denote like parts and the numeral 10 designates generally a rigid non-rotative central supporting post and, as appears from Fig. 3, the central post 10 comprises an inner tubular member 11 surrounded by an outer reinforcing element 12. The latter is a double walled structure providing adequate structural reinforcement for the tube 11 and its upper end serves as a rest for the lower one of a pair of axially spaced roller bearings 14 and 15.

A support drum 16 is mounted on the bearings 14 and 15 for free rotation concentrically of the support post 10 and has a plurality of radiating bifurcated brackets 18 whose outer ends pivotally support car suspension arms 20. The post assembly 10 is reinforced and held in rigid vertical position by bracing struts 21 which extend obliquely from the upper end of the post to a base frame 22. The structure may be further reinforced by other oblique struts 23 which extend obliquely from a point part-way up the post 10 to the base 22.

It is desired to have the cars assume a particular circular or circumferential arrangement when at rest to permit the accommodation of a predetermined number of cars without interference, and to this end a circular tubular spacing element or ring 25 is provided. As appears from Fig. 4 the ring 25 rests on a plurality of supporting rollers 26 and is retained in a concentric condition by guide rollers 27. The rollers 26 and 27 are mounted for free rotation on a support bracket 30 which is in turn supported by a truss arrangement comprising bars 32 and 33 which extend from the angle bracket 30 to spaced points along the bracing struts 21. The bracket 30 with its supporting trusses 32, 33 comprises a further reinforcement of the entire framework of the ride.

As appears from Fig. 1, individual passenger cars 40 are suspended from the several arms 20 by means of upper and lower flexible chain elements 41 and 42 and an intermediate cable 43, which need not possess the degree of flexibility of the chain elements 41 and 42. It will be noted from Fig. 1 that when centrifugal force begins to act upon the cars, they first swing outwardly 55 along an arc described from the points of engagement of the chains 42 with the tubular ring

25. After they reach a position where the chain elements 42 are straight, further outward and upward movement is along an arc tangential to the first arc but having its center at the axis of the pivotal connection between supporting arms 20 and brackets 48 of the rotatable drum 16.

In conventional aerial rides where the cars are suspended vertically from their upper support means, the support means must be as large in diameter as the diameter of the circular position which the cars assume at rest. This, of course, greatly complicates the construction and materially increases the lever arm of the pull of the cars on the support structure. Further, in conventional arrangement the cars move outwardly and upwardly about a long radius struck from the upper point of connection with the rotatable support. Since this large arc begins more or less tangential to the ground or supporting base, it requires a very large circular area to permit the cars to move outwardly and upwardly without interference.

By virtue of the provision of the tubular ring 25, resulting as it does in a compound arcuate movement of the cars in their ascension, any desired number of cars may be used without increasing the diameter of the upper support structure. Further, since the cars rise much more sharply from their position of rest by virtue of the compound arcuate movement, a much less area is required for a ride of a given capacity.

The drum 16 and all of the car suspension and support structures carried thereby are positively rotated by means of a gear 45 secured to the drum 16 and a pinion 46 which meshes therewith. A vertical drive shaft 47 extends alongside the central post 10 and is supported by the post through bearing brackets 48. The pinion 46 is secured to the upper end of drive shaft 47 and a bevel gear 50 is provided at its lower end.

A driving motor 51 connects with a combined clutch-brake unit 52 of conventional construction and manual means 53 are provided for controlling clutching and braking action. The driven side of the clutch-brake unit 52 engages a conventional reducing gear 54 whose output shaft carries a bevel pinion 55 which meshes with the bevel gear 50 of the driving shaft 47.

A cam mechanism is designated generally 58 in Fig. 1 and is shown in detail in the cross sectional enlargement, Fig. 3. When the cars are in the rest positions illustrated in Fig. 1 the cam mechanism 58 is supported in an upper position so as to be of no effect, in a manner which will presently appear. In the form illustrated in Figs. 1 and 3 each of the car suspension arms 20 has an inner extension 61 provided with a cam follower roller 62.

As operation of the ride proceeds and the cars 40 accelerate, they move upwardly and outwardly by pivotal movement of their supporting arms 20, under the influence of centrifugal force, until the arms 20 and the chains and cables extending therefrom assume a position approaching the horizontal. The ride is then at normal operating speed and ready to have the cam mechanism 58 brought into play to modify the until now continuous circular movements of the cars. The cam mechanism serves to impart periodic supplementary oscillations to the arms 20 through their extensions 61.

Referring particularly to Fig. 3 the numeral 65 designates a cam mechanism supporting tube which is axially moveable within the stationary tubular member 11 but is held against relative

5 rotation by a roller 66 which is carried by supporting tube 65 and engages a vertical slot 67 in the tubular member 11. The cam mechanism support tube 65 is normally biased to its upper limit of movement, the position shown in Fig. 1, by a compression coil spring 70 which rests on an annular seat 71 fixed to the rigid tubular member 11 and whose upper end bears against a flange 73 which is part of a cup shaped member 74 rigidly secured to the cam mechanism supporting tube 65.

10 For lowering the cam mechanism, the lower end of supporting tube 65 has a cable 75 attached thereto. The cable 75 passes downwardly and about a pulley (not shown) and thence laterally to a further guide pulley 77, from which it passes to a conventional winch 78. By clockwise rotation of a handle 79 of the winch, the cable 75 may be wound on the drum thereof to lower the cam mechanism against the resistance of spring 70.

15 The cam itself comprises a generally radial annular plate 80 which is formed to undulate circumferentially. The undulations are provided by a pair of downwardly directed cam lobes, one of which appears at 81 in Fig. 3. The cam 80 has secured rigidly thereto, as for instance, by welding, a concentric bearing sleeve 82 which is mounted for free rotation on the cam mechanism supporting tube 65 by means of anti-friction bearings 83. At its upper end the tube 65 is capped by a plate 85 which serves as a support for various cam controlling instrumentalities. The cam 80 has secured to its upper surface an internal ring gear 86 which meshes with a pinion 87 supported for free rotation by a bracket 88 secured to the non-rotatable support plate 85. A gear 89 is fixed for coaxial rotation with pinion 87 and meshes with a pinion 90 which serves to drive a turntable 91. The turntable 91 and the drive shaft connecting it with pinion 90 are supported by a bracket 92 likewise carried by support plate 85.

20 When the cam mechanism begins to lower, it does not impart full amplitude oscillations to support arms 20 and accordingly a greater relative speed as between the cam 80 and the rotating car support structure is permissible. During this phase of operation it is desired to hold the cam 80 fixed against any rotation so that the effective relative rotation between cam 80 and the cam followers 62 will be exactly equal to the speed of rotation of the car supporting structure, including the cam followers 62. To this end the turntable 91 is provided with a radial brake shoe 100 carried by a lever 101 whose opposite end is pivotally connected to a bracket 102 which is in turn rigidly connected to support plate 85.

25 The lever 101 has an intermediate pivotally connected link 103 and the latter is connected to one end of a lever 104 which is pivotally supported at a medial point by a bracket 105. A compression coil spring 106 seats on the bracket 105 and bears against lever 101 to normally engage brake shoe 100 against the turntable 91 and prevent rotation thereof. The opposite end of lever 104 is in a position to be engaged by the head of a screw 108 carried by a bar 110. The bar 110 has a collar 111 fixed thereto and downward movement of bar 110 is limited by engagement of collar 111 with a hub 112 which forms part of a bracket 113 which is rigidly secured to the stationary tubular member 11. As lowering movement of the cam mechanism proceeds and approaches a maximum, the left end of lever 104,

as viewed in Fig. 3, abuts the head of screw 108, and continued lowering movement of the cam mechanism releases the brake shoe 100 through link 103. When the cam mechanism is in a raised position the bar 110 is raised upwardly with it because the head of screw 108 is larger than the opening in support plate 85 through which the bar passes. This renders the screw 108 accessible for adjustment at all times.

The effect of freeing brake shoe 100 is to free the turntable 91 for free rotation and this obviously frees the cam 80 for free rotation since its previously fixed condition was maintained, through the intermediate gearing 87, 89, 90, by the action of the brake shoe 100 against turntable 91. The tendency then will be for the cam 80 to rotate synchronously with the support drum 16. This is due to the fact that the resistance of arms 20 to upward movement will cause the cam followers 62 to seek and retain the dwell points between the lobes 81 of the cam.

It is not desired to entirely negative the action of cam 80 but merely to reduce the periodicity of the impulses which it imparts to arms 20 through the followers 62. The reason for desiring to reduce this periodicity is the increase in amplitude of the oscillation of arms 20 when cam 80 is in a fully lowered position. It will be clear from the foregoing that the periodicity of supplemental oscillation of arms 20 will be at a maximum when the cam is held fixed and will reduce as the cam is permitted to rotate at increasing speeds.

The following mechanism is provided for the purpose of insuring some relative rotation between the cam 80 and the support structure generally, such relative rotation being adjustable as will presently appear. In the illustrative instance this is accomplished by permitting the cam to rotate at a speed less than the speed of rotation of the car support structure; the different in their speeds being the speed of relative rotation of the cam. An annular brake drum having an internal braking surface is designated 120 in Fig. 3 and is rigidly supported by the bracket 102.

The brake drum 120 is concentric with turntable 91 and the latter has brackets 121 which pivotally support rocker arms 122 which include brake shoes 123. The mass of the brake shoes 123 is such that centrifugal force, due to rotation of the turntable 91 by the arms 20 through the medium of the cam 80, tends to urge the shoes 123 into braking engagement with brake drum 120. This centrifugal urge is partly counteracted by coil springs 125 which engage against levers 122 and have suitable anchorage on pins 126 which are supported by brackets 127 and engaged slideably with the upper ends of levers 122. Nuts 128 may be threaded along pins 126 for varying the resilient urges of the several springs 125.

From the foregoing it will be seen that as soon as turntable 91 tends to exceed a predetermined speed, which speed will be less than the normal operating speed of the arm support structure, the brake shoes 123 will overcome the resistance of springs 125 sufficiently to engage against the brake surface of drum 120 and thus restrict the speed of turntable 91 and consequently the speed of cam 80. The gearing between cam 80 and turntable 91 causes the latter to move at a considerably higher velocity than the cam 80, so that centrifugal forces of sufficient magnitude may be generated in brake shoes 123 to effect the desired results.

While a preferred form of driving and controlling the cam element has been shown in the drawings and described in detail herein, it will be understood by those skilled in the art that an independent motor, direct gearing from the main drive motor, or any other suitable means may be employed without departing from the broader aspects of novelty of this phase of the present invention.

- 10 As shown in detail in Fig. 2, the upper supporting chains 41 comprise a single length of chain for each car 40, such chain extending over a pair of pulleys 130 supported at the opposite ends of a bar 131. Each bar 131 extends in the normal direction of movement of the cars and is rigidly attached to the outer end of an associated support arm 20. Provision is made for relative lateral displacement of adjacent cars by means of what is known in the art as an equalizing drum 132. This drum comprises essentially means for yieldably paying out a cord, cable or the like 133, the drum being secured to the chain 41 of one car and the element 133 extending to the adjacent chain 41 of the adjacent car. Because of the 15 action of cam 80, the undulations of the several cars follow sequentially and are not synchronous. Hence the elevations of adjacent cars will vary and the equalizing drum 132 permits such variation while normally tending to align the cars.
- 20 Because the center of mass of each car is between its supporting chains and cables, if a particular car swings forwardly of its supporting arm 20, as when the support structure is more or less suddenly decelerated, the car will swing in 25 the manner of a pendulum. That is, its front end will rise above the back end, and this eliminates any possibility of occupants tending to "pitch" with the cars under these conditions, which would be a hazard if the fore-and-aft suspension of each 30 car were of fixed relative length. This action of each individual car is permitted by virtue of the presence of the pulleys 130, which incorporate yieldable braking means (not shown), and are 35 commercially available and known in the art as 40 chain pocket wheels.

Each car is preferably provided with a fixed vertical fin as indicated at the rear ends of the cars 40 in Fig. 1, the fins being designated 136. The fins 136 serve as airfoils tending to align 45 the cars longitudinally against various forces tending to misalign them during their undulating circular travel. In the form illustrated in Fig. 1 the cars 40 are provided with curving overhead rails 137 which serve as convenient anchorages 50 for the chains 42, assist in giving support to the fins 136, and provide convenient means to be 55 grasped by patrons in entering or leaving the cars.

Fig. 5 shows an alternative support arm arrangement which provides for a yieldable application of the camming effect described above in the case of Figs. 1 and 3. As shown in Fig. 5, each supporting bracket 18, which, as in Figs. 1 and 3, is a radially extending part of rotatable drum 16, has a supporting arm 140 pivoted thereto. A cam follower arm 141 having a cam follower 142 is likewise pivoted to bracket 18 but, while a common pivot axis may be employed as illustrated in Fig. 5 the arm 140 and cam follower arm 141 are not fixed for joint pivotal movement. Cam follower 141 forms part of a truss bracket 143 of generally triangular form. The bracket 143 has pivotal connection as at 144 with a rod 145 which has a compression coil spring 146 disposed thereabout. The opposite end of rod

145 extends freely through an opening in a lug 147 on arm 140. One end of spring 146 seats against lug 147 and the opposite end is anchored to rod 145 as by a nut 148 which may be adjusted along rod 145 to vary the initial tension of spring 146.

It will be seen from the foregoing that when arm 140 sufficiently resists the tendency of cam 80 to move it in a counterclockwise direction through the intervention of follower 142, bracket 143 and spring 146, the excess or all of the movement of cam follower arm 141 in a counterclockwise direction will merely be absorbed in an additional stress spring 146.

What is claimed is:

1. Amusement apparatus comprising a support and means for rotating said support about a vertical axis, passenger carrier means, including a flexible suspension depending from said support at a predetermined radial distance from said axis, a spacing ring concentric with the axis of said support and disposed substantially below the upper end of said suspension, said spacing ring being of substantially greater radius than said radial distance whereby to positively engage said passenger carrier means as the latter moves to rest position to dispose the carrier a predetermined radial distance from said axis in rest position.

2. Amusement apparatus comprising a support and means for rotating said support about a vertical axis, passenger carrier means including a suspension depending from said support at a predetermined radial distance from said axis, a spacing ring concentric with the axis of said support and disposed substantially below the upper end of said suspension, said spacing ring being of substantially greater radius than said radial distance whereby to positively engage said passenger carrier means as the latter moves to rest position to dispose the carrier a predetermined radial distance from said axis in rest position.

3. Amusement apparatus comprising a support and means for rotating said support about a vertical axis, passenger carrier means including a flexible suspension depending from said support, a freely rotatable spacing ring concentric with the axis of said support and disposed substantially below the upper end of said suspension whereby to be engaged by said passenger carrier means as the latter moves to rest position to dispose the carrier a predetermined radial distance from said axis in rest position.

4. Amusement apparatus comprising a support and means for rotating said support about a vertical axis, passenger carrier means including a suspension depending from said support, a freely rotatable spacing ring concentric with the axis of said support and disposed substantially below the upper end of said suspension whereby to be engaged by said passenger carrier means as the latter moves to rest position to dispose the carrier a predetermined radial distance from said axis in rest position.

5. Amusement apparatus comprising a support and means for rotating said support about a vertical axis, a passenger carrier, means for suspending the carrier from said support at a predetermined radial distance from said axis whereby the carrier may move upwardly and outwardly under the influence of centrifugal force when said support is rotated, and a spacing ring concentric with the axis of said support, said spacing ring being of substantially greater radius than said radial distance and disposed substantially

below the upper end of the suspension means whereby to be engaged by said suspension means as the carrier moves to rest position and thereby space the carrier a predetermined radial distance from said axis in rest position.

6. Amusement apparatus comprising a support and means for rotating said support about a vertical axis, a passenger carrier, flexible means for suspending the carrier from said support at a predetermined radial distance from said axis whereby the carrier may move upwardly and outwardly under the influence of centrifugal force when said support is rotated, and a spacing ring concentric with the axis of said support, said spacing ring being of substantially greater radius than said radial distance and disposed substantially below the upper end of the suspension means whereby to be engaged by said suspension means as the carrier moves to rest position and thereby space the carrier a predetermined radial distance from said axis in rest position.

7. Amusement apparatus comprising a support and means for rotating said support about a vertical axis, a passenger carrier, means for suspending the carrier from said support whereby the carrier may move upwardly and outwardly under the influence of centrifugal force when said support is rotated, and a freely rotatable spacing ring concentric with the axis of said support and disposed substantially below the upper end of the suspension means whereby to be engaged by said suspension means as the carrier moves to rest position and thereby space the carrier a predetermined radial distance from said axis in rest position.

8. Amusement apparatus comprising a support and means for rotating said support about a vertical axis, a passenger carrier, flexible means for suspending the carrier from said support whereby the carrier may move upwardly and outwardly under the influence of centrifugal force when said support is rotated, and a freely rotatable spacing ring concentric with the axis of said support and disposed substantially below the upper end of the suspension means whereby to be engaged by said suspension means as the carrier moves to rest position and thereby space the carrier a predetermined radial distance from said axis in rest position.

9. Amusement apparatus comprising a rotatable support, a plurality of passenger carriers, means suspending each carrier from said support whereby the carrier may move upwardly and outwardly under the influence of centrifugal force when said support is rotated, means acting against the suspension means for imparting a vertical to and fro component of movement thereto to cause each carrier to pursue an undulating circular course, the suspension means for each carrier including means extending upwardly from fore and aft points on said carrier and pulley means, said fore and aft upwardly extending means having a flexible connecting portion extending over said pulley means, whereby the effective relative lengths of the fore and aft upwardly extending means may vary to permit raising of one end of the carrier relative to the other, and yieldably extensible means engaging between adjacent carriers for yieldably restraining movement of said carriers out of alignment either vertically or horizontally.

10. Amusement apparatus comprising a rotatable support, a plurality of passenger carriers, means suspending each carrier from said support whereby the carrier may move upwardly and out-

wardly under the influence of centrifugal force when said support is rotated, said suspension means comprising arm means pivoted to said support, a pair of pulley elements carried by said arm means and spaced in the direction in which said arm means are rotated by said support, and a continuous suspension element extending upwardly from the front portion of the carrier, over both pulleys and down to the rear portion of the carrier, whereby each carrier may change its longitudinal attitude by movement of said suspension element on said pulleys, and yieldably extensible means engaging between adjacent carriers for yieldably restraining movement of said carriers out of alignment either vertically or horizontally.

11. Amusement apparatus comprising a rotatable support, a plurality of passenger carriers, and means suspending each carrier from said support whereby the carrier may move upwardly and outwardly under the influence of centrifugal force when said support is rotated, said suspension means including a pair of pulley elements spaced in the direction in which said arm means are rotated by said support and a continuous suspension element extending upwardly from the front portion of the carrier, over both pulleys and down to the rear portion of the carrier, whereby each carrier may change its longitudinal attitude by movement of said suspension element on said pulleys, and yieldably extensible means engaging between adjacent carriers for yieldably restraining movement of said carriers out of alignment either vertically or horizontally.

12. Amusement apparatus comprising a rotatable support, a plurality of passenger carriers, and means suspending each carrier from said support whereby the carrier may move upwardly and outwardly under the influence of centrifugal force when said support is rotated, said suspension means including pulley means and a continuous suspension element extending upwardly from the front portion of the carrier, over the pulley means and down to the rear portion of the carrier, whereby each carrier may change its longitudinal attitude by movement of said suspension element on said pulleys, and yieldably extensible means engaging between adjacent carriers for yieldably restraining movement of said carriers out of alignment either vertically or horizontally.

13. Amusement apparatus comprising a rotatable support, a plurality of passenger carriers, means suspending each carrier from said support whereby the carrier may move upwardly and outwardly under the influence of centrifugal force when said support is rotated, and a rotatable spacing ring concentric with the axis of said support and disposed substantially below the upper ends of the suspension means to be engaged by said suspension means as the carriers move to rest position during deceleration, whereby the carriers are retained in alignment in a circle of predetermined diameter with the suspension means arrested in an oblique position.

14. Amusement apparatus comprising a rotatable support, a plurality of passenger carriers, means suspending each carrier from said support whereby the carrier may move upwardly and outwardly under the influence of centrifugal force when said support is rotated, a rotatable spacing ring concentric with the axis of said support and disposed substantially below the upper ends of the suspension means to be engaged by said

suspension means as the carriers move to rest position during deceleration, whereby the carriers are retained in alignment in a circle of predetermined diameter with the suspension means arrested in an oblique position, and means acting against the several suspension means for imparting an up and down component of movement to cause the carriers to pursue an undulating circular course.

- 10 15. Amusement apparatus comprising a support and means for rotating said support about a vertical axis, passenger carrier means including a suspension depending from said support, a spacing ring concentric with the axis of said support and disposed substantially below the upper end of said suspension to be engaged by said passenger carrier means as the latter moves to rest position to dispose the carrier a pre-determined radial distance from said axis in rest position, and means rotatably supporting said spacing ring independently of said first-mentioned support.
- 15 16. Amusement apparatus comprising a rotatable support, a plurality of passenger carriers, means suspending each carrier from said support whereby the carrier may move upwardly and outwardly under the influence of centrifugal force when said support is rotated, said suspension means comprising arm means pivoted to said support, pulley means carried by said arm means and rotatable in a plane substantially along the path of movement of the suspension means as the support is rotated, and a flexible suspension element extending over said pulley means and downwardly to support each carrier, whereby
- 20 25 30 35 40 45 50 55 60

- 30 35 40 45 50 55 60
- said carrier may swing ahead of or fall behind its associated arm means during rotation thereof, and yieldably extensible means engaging between adjacent carriers for yieldably restraining movement of said carriers out of alignment either vertically or horizontally.
17. Amusement apparatus comprising a support and means for rotating said support about a vertical axis, passenger carrier means including a flexible suspension depending from said support, a spacing ring concentric with the axis of said support and disposed substantially below the upper end of said suspension means whereby portions of said passenger carrier means engage portions of said spacing ring as the former moves to rest position to dispose the carrier a predetermined radial distance from said axis in rest position, one of said engaging portions being rotatable to provide anti-friction engagement therebetween.
